[57] CLAIM

The ornamental design for a combined speaker enclosure and pedestal stand, as shown and described.

DESCRIPTION

FIG. 1 is a perspective view of a combined speaker enclosure and pedestal stand showing my new design;

FIG. 2 is a front elevational view thereof;

FIG. 3 is a rear elevational view thereof;

FIG. 4 is a top view thereof; and,

FIG. 5 is a right side elevational view with the left side being a mirror image thereof.

The bottom view of the combined speaker enclosure and pedestal stand is planar and unornamented.

FIG. 1

FIG. 2

FIG. 3

FIG. 4

FIG. 5
